UNITED STATES PATENT OFFICE.

CHARLES H. HODGES, OF DETROIT, MICHIGAN, ASSIGNOR TO THE DETROIT STEAM RADIATOR COMPANY, OF SAME PLACE.

DESIGN FOR RADIATOR ORNAMENTATION.

SPECIFICATION forming part of Design No. 18,311, dated May 15, 1888.

Application filed June 10, 1887. Serial No. 240,951. Term of patent 7 years.

To all whom it may concern:

Be it known that I, CHARLES H. HODGES, a citizen of the United States, residing at Detroit, in the county of Wayne and State of Michigan, have invented and produced a new and original sign for Radiators, of which the following is a specification, reference being had to the accompanying drawings, forming part thereof:

10 In the drawings, Figure 1 is a view in elevation of a single pipe or loop radiator illustrating my design, and Fig. 2 is a perspective view of a multiple-loop radiator, the same arrangement of ornamentation being shown in both figures.

15 My design consists in a radiator having a section of ornamental leaves at the top and at the bottom of each vertical radiator pipe or loop, and a vertical rib or bead traversing the 20 surface of the pipe or loop between the upper and lower sections of ornamentation, and connecting the same.

A designates the top section of ornamental leaves, B the bottom section of ornamental leaves, and C the vertical rib or bead upon the 25 single pipe or loop radiator, while A', B', and C' designate the corresponding ornamental features of the multiple-loop radiator.

What I claim is—

The design for a radiator, which consists in 30 a section of ornamental leaves at the top and bottom of each vertical radiator pipe or loop, and a vertical rib or bead between the upper and lower sections of ornamentation, and connecting the same, as herein shown and described.

In testimony whereof I sign this specification in the presence of two witnesses.

CHARLES H. HODGES.
